Carpet Sweeper Company, Grand Rapids, Mich.

Application February 25, 1954, Serial No. 29,214

Term of patent 14 years

(Cl. D9—2)

To all whom it may concern:

Be it known that I, Frederick W. Hertzler, a citizen of the United States, residing at Detroit, in the county of Wayne and State of Michigan, have invented a new, original, and ornamental Design for a Carpet Sweeper, of which the following is a specification, reference being had to the accompanying drawing, forming part thereof, in which:

Fig. 1 is a front perspective view;

Fig. 2 is a rear perspective view; and

Fig. 3 is an elevational view of a carpet sweeper of my design, the handle in all three views being collapsed rearwardly.

I claim:

The ornamental design for a carpet sweeper, as shown.
